ENGINE

Harold H. Timian, Detroit, Mich., assignor to
 Continental Motors Corporation, Detroit, Mich.,
 a corporation of Virginia

Application June 4, 1931, Serial No. 542,014

28 Claims. (CL 123—52)

This invention relates to engines and more particularly to an intake manifold structure therefor for distributing and conducting the fuel mixture to the engine cylinders.

Difficulty has been experienced in distributing a fuel mixture to the cylinders of an internal combustion engine in such a way as to insure a uniform supply of fuel mixture to the cylinders at all engine speeds. With the event of the six and eight cylinder engines it has been necessary to provide a manifold structure with a plurality of branches for distributing the fuel to the cylinders and much difficulty has been experienced in accurately dividing and distributing the fuel to the branches. Some devices have been developed for controlling the fuel flow intermediate the riser and the point where the fuel is distributed into the manifold branches which distribute the fuel over the runner wall in the form of a film of uniform depth but this has not proven entirely satisfactory since it has not been possible to accurately control this flow of fuel so that the same will flow as desired, since very often the fuel flow becomes stratified to some extent thereby preventing the accurate division and distribution of the fuel into the manifold branches. Where the fuel is induced to flow in certain stratas difficulty has been experienced in properly confining the stratified fuel flow to a certain path so that the same can be accurately divided and distributed to the respective manifold branches.

It is an object of my present invention to provide a manifold construction in which the fuel mixture is induced to flow along certain defined paths for proper distribution in the manifold branches.

Another object of my present invention is to provide a manifold structure with means for positively stratifying the fuel flow and dividing said stratified fuel flow for conducting predetermined amounts of the fuel into said manifold branches for conducting substantially equal amounts of fuel to the engine cylinders connected therewith.

For a more detailed understanding of my invention, reference may be had to the accompanying drawings which illustrate one form which my invention may assume, and in which:

Fig. 1 is a fragmentary side elevational view of an internal combustion engine equipped with a fuel mixture forming device and an intake manifold structure constructed in accordance with my invention,

Fig. 2 is a horizontal sectional view taken on the line 2—2 of Fig. 1,

Fig. 3 is a fragmentary sectional view of a modified construction,

Figs. 4, 5 and 6 are detail sectional views taken on the lines 4—4, 5—5, and 6—6 respectively of Fig. 2,

Figure 4^a is a fragmentary sectional view showing a modified groove construction that terminates substantially mid-way between the riser and fuel dividing and distributing means,

Figure 7 is an elevational view of a manifold structure illustrating a modified form of construction,

Figure 8 is a vertical sectional view taken on the line 8—8 of Fig. 7,

Figure 9 is a detail sectional view taken on the line 9—9 of Fig. 8,

Figure 10 is a horizontal sectional view taken on the line 10—10 of Figure 7, and

Figure 11 is a vertical sectional view taken on the line 11—11 of Figure 8.

The manifold structure A illustrated in Figures 1 to 6 inclusive is adapted for assembly with an internal combustion engine which includes in general an engine casting 10 having a plurality of intake passages and exhaust passages 11 and 12 respectively. A fuel mixture forming device 13 is associated with the engine and is provided with a header 14 adapted for connection with the manifold riser 15, said riser terminating in a fuel mixture distributing chamber.

The manifold structure A consists of manifold branches 16 and a runner 17, said runner being adapted for communication with the riser portion 15 and the branches 16. The fuel mixture is introduced into the riser 15 from the fuel mixture forming device and is adapted to be spilled over the edge formed by the intersecting walls of the riser and runner, the fuel being then conducted through the runner to a point adjacent the intersection of the manifold branches where the same is divided and accurately distributed into said branches.

I find it advisable in a manifold construction adapted for association with a multi-cylinder engine of the six and eight cylinder type to provide branches which will intersect at a point remote from the riser. In order to properly distribute the fuel mixture to said branches I find it desirable to induce a stratified fuel flow in the runner which I find may be more conveniently divided and distributed into the manifold branches. In order to facilitate the accurate division and distribution of the stratified fuel flow, I preferably

provide fuel conducting means for confining the stratified fuel flow in a defined path. This is accomplished by providing a wet fuel conducting groove 18 in the floor of the runner, said groove 5 terminating preferably adjacent the intersection of the manifold branches and as shown in Fig. 2 the stratified fuel flow is directed against the split 19 for dividing the same and causing the desired distribution of the fuel into the manifold branches 10 16. If desired the manifold may be constructed as shown in Fig. 3 in which a groove 18' is forked as at 20, each branch of the groove beyond the fork being directed part way into the manifold branches. In order to induce a stratified fuel 15 flow in the runner I have preferably provided means which induce the major portion of the fuel to spill over the edge formed by the intersecting walls of the runner and riser at a certain definite point along this edge. Preferably the groove in the runner is extended to the riser and connects with a partial groove in the riser, said 20 riser groove and runner groove being connected by a bend of relatively greater curvature than the remaining edge portion. Figs. 4 and 5 illustrate 25 this part of my invention and the fuel introduced in the riser is conducted therethrough and caused to flow in the communicating runner of the manifold structure. Much of this fuel at low engine speeds is carried along the walls of the riser and 30 will be more readily spilled over a rounded corner if the same is constructed with a large radius than over a corner constructed with a small radius.

Thus the manifold construction as illustrated 35 in these figures induces a stratified fuel flow preferably conducted substantially centrally of the runner.

In the Figures 7 to 11 inclusive I have provided a primary fuel mixture conducting or riser portion 30 communicating with a runner 31. In this 40 manifold construction the manifold branches 32 are preferably arranged substantially perpendicular to the runner 31 and the runner is provided with a groove 32' constructed in accordance with the principle illustrated in the Figures 1 to 6 inclusive. In this case, however, the groove 32' is branched as at 33 forming branches 34 which extend part way into the manifold branches and 45 preferably extend substantially perpendicular to the groove 32'. In this construction as in the construction illustrated in Figures 1 to 6 inclusive the groove 32' in the runner interconnects with the groove 35 in the riser, said groove being connected with a rounded bend of a greater radius than the bend between the remaining floor portion 50 of the runner and the riser wall. In this modified construction the runner and manifold branches are preferably constructed substantially circular in cross-section and the grooves which 55 are located substantially in the vertical longitudinal planes of said runner and branches respectively are thus constructed to more readily control the fuel flow and to cause the same to flow in a manner found to be most desirable for proper fuel distribution to the cylinders. This modified 60 construction provides a manifold structure consisting of a runner or header 31 extending generally laterally of the engine and branches 32 extending longitudinally of the engine connecting the extremities of the header with the engine 65 cylinders. Preferably the riser, header, and branches extend substantially at right angles to each other.

In some manifold constructions the groove in 70 the runner may terminate at a point about mid-

way between the riser and the fuel dividing and distributing means. The groove in the runner may be sloped as shown in Figure 4^a if so desired, said groove extending outwardly and upwardly with respect to the distributing chamber at the junction of the riser and runners.

At relatively low engine speeds there is a relatively greater percentage of wet fuel flowing along the floor of the runner, and consequently is principally concentrated at the groove. Preferably this groove is provided with substantially vertical side walls, the edge formed by the intersecting side walls of the groove and floor of the runner being fairly sharp, said edge having a relatively small radius. As the engine speed is increased the inertia forces are increased, and when said inertia forces of the fuel become greater than the capillary forces, the fuel particles are thrown out of the groove in the form of a stratified mist into the central portion of the runner and 10 directly into the vaporized fuel stream. It may be noted that as the inertia forces increase, due to the increase in engine speed, these forces in particular overcome the capillary attraction at the bend and thus some of the fuel is thrown off 15 instead of adhering to the floor of the groove. The fuel is thrown off in a plurality of directions substantially in a common plane thereby inducing a stratified mist in the runner. At relatively high engine speeds this stratified fuel mist may 20 sometimes be thrown against the roof of the runner. Preferably the slope of the groove is such as to throw this fan-like stratified mist so as to cause the same to impinge the top wall or 25 roof at or adjacent to the split or fuel mixture flow dividing and distributing means.

Thus, the fuel flow controlling means as shown in the illustrated embodiment of my invention induces a stratified fuel flow at substantially all 30 engine speeds. Where a groove is employed solely at the bend between two adjacent fuel conducting manifold portions, approximately the same 40 result is obtained except that the fuel particles are thrown off at a steeper angle to the floor of the runner.

It may be further noted that the construction shown in the illustrated embodiment of my invention provides a positive control for the fuel flow thereby insuring the uniform distribution of fuel to a plurality of engine cylinders at all 45 engine speeds.

It will be apparent to those skilled in the art to which my invention pertains that various modifications and changes may be made therein without departing from the spirit of my invention or 50 from the scope of the appended claims.

What I claim as my invention is:

1. An intake manifold structure for an internal combustion engine having a fuel mixture forming device and including a runner communicating with said fuel mixture forming device, and wet fuel conducting means extending substantially the full length of the runner for inducing a stratified fuel flow in a predetermined defined path longitudinally of the runner for distributing the fuel to the engine.

2. An intake manifold structure for an internal combustion engine having a fuel mixture forming device and including a runner communicating with said fuel mixture forming device, and wet fuel conducting means extending substantially the full length of the runner for inducing a stratified fuel flow centrally and longitudinally of the runner for distributing the fuel to the engine.

3. An intake manifold structure for an internal

- combustion engine having a fuel mixture forming device and including a runner communicating with said fuel mixture forming device, and wet fuel conducting means extending substantially 5 the full length of the runner for inducing a stratified fuel flow in said runner adjacent the floor of the runner at relatively low engine speeds for distributing the fuel to the engine.
4. An intake manifold structure for an internal 10 combustion engine having a fuel mixture forming device and including a runner communicating with said fuel mixture forming device, manifold branches communicating with the runner, wet fuel conducting means inducing a definite stratified fuel flow in said runner, and means dividing 15 said stratified fuel flow and directing same into said manifold branches.
5. An intake manifold structure for an internal 20 combustion engine having a fuel mixture forming device and including a runner communicating with said fuel mixture forming device, manifold branches communicating with the runner, wet fuel conducting means inducing a definite stratified fuel flow in said runner, and means adjacent 25 the intersection of said manifold branches for dividing said fuel flow and directing same into said manifold branches.
6. An intake manifold structure for an internal 30 combustion engine having a fuel mixture forming device and including a runner communicating with said fuel mixture forming device, said runner provided with a wet fuel conducting groove of relatively shallow depth for inducing a stratified wet fuel flow in said runner during the operation 35 of the engine for distributing same.
7. An intake manifold structure for an internal 40 combustion engine having a fuel mixture forming device and including a runner communicating with said fuel mixture forming device, said runner provided with a wet fuel conducting groove of relatively shallow depth and extending longitudinally thereof for inducing a stratified wet fuel flow in said runner during the operation of the 45 engine for distributing same.
8. An intake manifold structure for an internal 50 combustion engine having a fuel mixture forming device and including a runner communicating with said fuel mixture forming device, manifold branches communicating with the runner, said runner provided with a wet fuel conducting groove of relatively shallow depth and extending longitudinally thereof for inducing a stratified wet fuel flow in said runner, said groove being constructed 55 adjacent the intersection of said manifold branches to distribute said fuel flow into said manifold branches.
9. An intake manifold structure for an internal 60 combustion engine having a fuel mixture forming device and including a runner communicating with said fuel mixture forming device, manifold branches communicating with the runner, said runner provided with a groove extending longitudinally thereof for inducing a stratified fuel flow in said runner, said groove being forked adjacent 65 the intersection of said manifold branches to distribute said fuel flow into said manifold branches.
10. An intake manifold structure for an internal 70 combustion engine and including fuel mixture conducting portions disposed at an angle to each other in substantially the same horizontal engine plane and connected by a bend, and wet fuel distributing means adjacent the intersection of said fuel mixture conducting portions inducing a posi- 75
- tive stratified wet fuel flow around the bend during engine operation.
11. An intake manifold structure for an internal 5 combustion engine and including fuel mixture conducting portions disposed at an angle to each other in substantially the same horizontal engine plane and connected by a bend, said manifold provided with wet fuel distributing means constructed to induce a stratified wet fuel flow around the bend during engine operation. 10
12. An intake manifold structure for an internal 15 combustion engine and including fuel mixture conducting portions disposed at an angle to each other in substantially the same horizontal engine plane and connected by a bend, said manifold provided with a recessed wet fuel distributing groove of relatively shallow depth at the bend for inducing a positive stratified wet fuel flow around the bend during engine operation. 15
13. An intake manifold structure for an internal 20 combustion engine and including fuel mixture conducting portions disposed at an angle to each other in substantially the same horizontal engine plane and connected by a bend, said portions constructed substantially circular in cross section, 25 and wet fuel distributing means including a shallow groove adjacent the intersection of said fuel mixture conducting portions for inducing a stratified wet fuel flow centrally around said bend during engine operation. 20
14. An intake manifold structure for an internal 30 combustion engine having a fuel mixture forming device and including a riser portion communicating with said fuel mixture forming device, and a runner communicating with said riser portion, and means including a relatively shallow recess acting on said fuel mixture as the same flows over a bend connecting the riser portion with the runner to induce a stratified wet fuel flow centrally and longitudinally of the runner during engine operation. 35
15. An intake manifold structure for an internal 40 combustion engine having a fuel mixture forming device and including a riser portion communicating with said fuel mixture forming device, and a runner communicating with said riser portion and extending substantially in a plane at right angles to the axis of the riser portion, said riser and runner having interconnecting relatively shallow fuel distributing grooves to induce 45 a stratified wet fuel flow in said runner along a defined path during engine operation. 50
16. An intake manifold structure for an internal 55 combustion engine having a fuel mixture forming device and including a riser portion communicating with said fuel mixture forming device, and a runner communicating with said riser portion and extending substantially in a plane at right angles to the axis of the riser portion, said riser and runner having interconnecting continuous relatively shallow fuel distributing grooves 60 extending substantially in the vertical central longitudinal plane containing the runner and riser axes for inducing a stratified wet fuel flow in said runner during engine operation. 65
17. An intake manifold structure for a multi-cylinder internal combustion engine having a fuel mixture forming device, and including a riser communicating with said fuel mixture forming device, a plurality of manifold branches communicating with said engine cylinders, a runner interconnecting said branches and said riser, means remote from the riser and adjacent the intersection of said branches for dividing and distributing the fuel mixture in said branches, and 70 75

means acting on the fuel precipitate to induce a definite stratified wet fuel flow in said runner intermediate the riser and said fuel dividing and distributing means during engine operation for distributing the fuel to said branches.

18. An intake manifold structure for a multi-cylinder internal combustion engine having a fuel mixture forming device, and including a riser communicating with said fuel mixture forming device, a plurality of manifold branches communicating with said engine cylinders, a runner interconnecting said branches and said riser, means remote from the riser and adjacent the intersection of said branches for dividing and distributing the fuel mixture in said branches, means adjacent said intersection for dividing and distributing wet fuel, the floor of said runner provided with a longitudinally extending relatively shallow groove for confining said wet fuel to flow in a definite defined path during engine operation at relatively low engine speeds for conduction to said fuel dividing and distributing means.

19. An intake manifold structure for a multi-cylinder internal combustion engine having a fuel mixture forming device, and including a riser communicating with said fuel mixture forming device, a plurality of manifold branches communicating with said engine cylinders, a runner interconnecting said branches and said riser, means remote from the riser and adjacent the intersection of said branches for dividing and distributing the wet fuel into said branches, said runner constructed to induce a definite stratified wet fuel flow therein during engine operation to conduct same to said wet fuel dividing and distributing means.

20. An intake manifold structure for an internal combustion engine having a fuel mixture forming device and including a runner communicating with said fuel mixture forming device, and means inducing a stratified fuel flow along the floor of the runner at relatively low engine speeds and for inducing a stratified fuel mixture flow above the floor of the runner at relatively high engine speeds.

21. An intake manifold structure including a distributing chamber, a runner and branches communicating with the cylinders of a multi-cylinder internal combustion engine, said runner communicating with said distributing chamber and said branches, means for dividing said fuel flow at a point remote from said distributing chamber, and a relatively shallow groove intermediate said distributing chamber and said fuel flow dividing means for inducing a definite stratified fuel flow toward the branches from said distributing chamber, said groove terminating ahead of the said fuel flow dividing means but remote from the junction of said distributing chamber.

22. An intake manifold structure including a distributing chamber, a runner and branches communicating with the cylinders of a multi-cylinder internal combustion engine, said runner communicating with said distributing chamber and said branches, means for dividing said fuel flow at a point remote from said distributing chamber, and a groove in the floor of said runner intermediate said distributing chamber and said fuel flow dividing means for inducing a definite stratified fuel flow, said groove terminating ahead of the said fuel flow dividing means.

23. A manifold structure including a distrib-

uting chamber, a runner having an inlet and outlet, said inlet communicating with said distributing chamber, said runner floor having a wet fuel flow conducting groove of relatively shallow depth and extending outwardly and upwardly with respect to the distributing chamber for inducing wet fuel flow toward the runner outlet.

24. An intake manifold structure for a multi-cylinder internal combustion engine and including a distributing chamber, a runner communicating with said distributing chamber, a plurality of branches communicating with said runner and with a plurality of engine cylinders, said runner having a relatively shallow wet fuel conducting groove extending outwardly and upwardly with respect to the distributing chamber and terminating ahead of the junction of said branches and said runner for conducting wet fuel toward said branches.

25. An intake manifold structure for a multi-cylinder internal combustion engine and including a distributing chamber, a runner communicating with said distributing chamber, a plurality of branches communicating with said runner and with a plurality of engine cylinders, means adjacent the junction of said branches and runner for dividing said fuel flow and distributing predetermined quantities to said branches, said runner having a wet fuel conducting groove extending outwardly and upwardly with respect to the distributing chamber and terminating ahead of the junction of said fuel flow dividing means.

26. An intake manifold structure for a multi-cylinder internal combustion engine and including a distributing chamber, means for applying heat to said distributing chamber, a runner having an inlet and outlet, said inlet communicating with said distributing chamber and extending beyond the influence of said heating means, said runner having a relatively shallow wet fuel conducting groove extending outwardly from said distributing chamber for conducting wet fuel toward said runner outlet.

27. An intake manifold structure for a multi-cylinder internal combustion engine and including a distributing chamber, means for applying heat to said distributing chamber, a runner communicating with said distributing chamber and extending substantially beyond the influence of said heating means, said runner constructed substantially rectangular in cross-section and having a relatively shallow wet fuel conducting groove in the floor thereof extending longitudinally of said runner outwardly from said distributing chamber for conducting wet fuel outwardly from said distributing chamber toward the engine cylinders.

28. An intake manifold structure for a multi-cylinder internal combustion engine and including a distributing chamber, a heating jacket substantially enclosing said distributing chamber, means for supplying hot gases to said heating jacket, a runner having an inlet and outlet, said inlet communicating with said distributing chamber, said runner extending substantially beyond the heating jacket, said runner having a relatively shallow wet fuel conducting groove extending longitudinally thereof from said distributing chamber for conducting wet fuel toward the runner outlet.

HAROLD H. TIMIAN.
